AUTOMATIC STARTING MECHANISM FOR
INTERNAL COMBUSTION ENGINESFrank T. Christian, Elmira, N. Y., assignor to
Eclipse Machine Company, Elmira, N. Y., a
corporation of New York

Application April 29, 1931, Serial No. 533,649

5 Claims. (Cl. 177—311)

This invention relates to automatic starting mechanism for internal combustion engines and more particularly to a device for protecting the starting mechanism and the source of electrical energy in case the engine fails to start after a predetermined time of cranking, or in case of an overloading of the starting mechanism such as would be caused by an attempt to start a motor vehicle with the transmission gears engaged and 10 the brakes set, or by a jamming of the starting gearing due to a failure to secure proper mesh thereof.

It is an object of the present invention to provide an automatic starting mechanism embodying 15 a novel means for opening the starting circuit after a predetermined amount of energy has been expended through the starting circuit without securing self-operation of the engine.

Another object is to provide such a device in 20 which the automatic opening of the starting circuit is secured by means of a heat-responsive device having a heating element in the starting motor circuit.

A further object is to provide such a device in 25 which when the safety device has functioned, the starting circuit will remain open until the operator has performed some act to close the break in the starting circuit.

Another object is to provide such a device which 30 furnishes an audible signal to warn the operator of the inoperative condition of the engine or starting mechanism and remind him to disconnect the automatic starting mechanism.

Further objects and advantages will be apparent 35 to those skilled in this art from the following description taken in connection with the accompanying drawings in which:

Fig. 1 is a semi-diagrammatic illustration of one preferred embodiment of the invention; the 40 automatic starting switch elements being shown in elevation and partly in vertical section; and

Fig. 2 is a similar view of a second embodiment of the invention.

In Fig. 1 there is illustrated a starting motor circuit including a battery 10, one terminal of which is grounded at 11 and the other terminal of which is connected by a lead 12 to an automatic starting mechanism comprising a starting switch having stationary elements 13 and 14 and a movable insulated bridging element 16. The lead 12 is connected to the stationary switch element 13, and the stationary element 14 is connected through a single turn coil 17 to a heating element 18, and this in turn is connected to the starting motor SM through a second switch comprising

stationary elements 19 and 21, and a movable, insulated bridging element 22.

The movable element 16 of the starter switch is mounted on a magnetic plunger 23 which is normally maintained in its upper position by means such as a spring 24 but which may be drawn down to close the starting switch by a solenoid 26. Said solenoid is included in a control circuit which when closed, causes the solenoid 26 to be energized to close the starting switch. This control 10 circuit comprises the battery 10, lead 12, ammeter A, manual switch 27 (which may, as indicated, be the ignition switch of the internal combustion engine) lead 28, solenoid 26, lead 29, fixed contact 31, movable contact 32, spring strip 33 and ground connection 34. The spring strip 33 is arranged to normally hold the contact 32 against the fixed contact 31 whereby closure of the manual switch 27 by the operator will cause energization of the 15 control circuit.

Means are provided for automatically opening the control circuit when the engine starts, for holding said circuit open as long as the engine is self-operative, and for delaying the closing thereof until a predetermined time after the engine 25 has come substantially to rest. As illustrated, these means include a wedge-shaped weight member 36 mounted on the end of the spring strip 33 in the path of movement of a roller 37. Said roller is mounted on the end of a lever 38 pivoted 30 at 39 and having a pin 41 at an intermediate point thereof projecting laterally between a pair of flanges 42 and 43 on a movable magnetic relay plunger 44. A voltage coil 46 and a generator coil 47 are arranged to surround the lower part of the 35 relay plunger 44 and, when energized, attract the same downwardly. The voltage coil 46 is connected at one end by a lead 48 to the stationary starting switch member 14, and is grounded at its other end at 49. Generator coil 47 is connected at one end by a lead 51 to the generator G and is also grounded at its other end at 49. Relay plunger 44 is normally retained in its upper position against a spacing sleeve 52 by means such as a spring 53 whereby the roller 37 is maintained 40 as illustrated out of contact with the weight member 36 so that the contact 32 normally rests against contact 31.

The movable member 22 of the second switch 50 member is biased toward open position by means such as a spring 54 and is adapted to be retained in closed position by means of a latch 56 pivoted at 57 and having a nose 58 adapted to engage under a terminal flange 59 of the switch member 22. The latch 56 is yieldably urged toward engag- 55

ing position by means such as a spring 61 engaging the free end thereof and adapted to move it toward a suitable stop member 62.

The latch 56 is adapted to be moved out of engaging position by means of an electro-magnet 63 suitably mounted adjacent the free end of said latch. One terminal of this electro-magnet is grounded as indicated at 64 and the other terminal is connected by means of a lead 66 to a fixed contact 67. A heat-responsive member 68 is fixedly mounted at one end in any suitable manner as indicated at 69 and is provided at its free end with a movable contact 71 adapted to engage the fixed contact 67. The heat-responsive member 68 is arranged within the heating element 18 of the starting circuit, and the contact 71 is electrically connected to the heating element as indicated at 70. The heat-responsive member 68 is so arranged that a rise in temperature thereof causes the free end to move contact 71 into engagement with the fixed contact 67 and thus energize the electromagnet 63 from the starting circuit.

In the normal operation of the device, closure of the ignition switch 27 closes the control circuit, thus causing the solenoid 26 to close the starting switch 13, 16, 14. This completes the starting circuit through the single turn coil 17, heating element 18, second switch 19, 22, 21, and starting motor SM whereby the starting motor is caused to crank the engine. During this time the voltage coil 46 is energized by reason of its connection to the starting switch member 14, but the heavy current traversing the single turn coil 17 holds the plunger 44 in its upper position. This holding effect is preferably controlled by means such as an adjustable magnetic pole piece 72 within the spacing member 52.

If the engine becomes self-operative after a reasonable amount of cranking, the load on the starting motor is thereupon relieved and the consequent reduction of the current through the single turn coil 17 together with the increase of voltage drop through the voltage coil 46 enables the latter to overcome the effect of the single turn coil 17 and the spring 53, and draw the plunger 44 downwardly. This causes the lever 38 to carry the roller 37 into engagement with the weight member 36 and bend the spring strip 33 backward sufficiently to move the contact 32 away from contact 31. The consequent opening of the control circuit causes the deenergization of the solenoid 26, thus releasing the starting switch plunger 23 whereupon the spring 24 operates to open the starting switch. The relay plunger 44 is not immediately released, however, since the voltage coil 46 is traversed by a slight amount of current generated by the starting motor spinning by momentum in its residual field, this current being sufficient to hold the plunger 44 against its pole piece 73 until the starting motor has come substantially to rest. Before the voltage coil 46 becomes entirely deenergized, the generator G which is driven from the engine builds up sufficient voltage to energize the generator coil 47 and retain the relay plunger 44 in its lower position, thus holding the contact 32 out of engagement with contact 31.

If the engine should stall for any reason, the generator coil 47 becomes deenergized and the spring 53 raises the relay plunger 44, releasing the weight member 36 which vibrates for a predetermined length of time due to its pendulous mounting on the spring strip 33, thus giving the engine time to come completely to rest. When

the vibration ceases and the contact 32 comes to rest against the contact 31, the starting operation is repeated.

If, however, when the ignition switch 27 is closed, the engine should fail to start owing to improper functional conditions or to a jamming of the starter gearing, the heating element 18 will gradually heat up the heat-responsive member 68 until the latter deflects sufficiently to cause contact 71 to engage contact 67. The consequent energization of the electro-magnet 63 causes the latch 56 to be swung out of engaging position whereby the movable switch member 22 is released and moves outwardly under the action of spring 54, thus breaking the starting circuit.

When the starting circuit is thus broken, the deenergization of the single turn coil 17 allows the voltage coil 46 to withdraw the relay plunger 44, thus opening the control circuit and releasing the starting switch. As soon as the starting switch opens, however, the voltage coil 46 is deenergized and the spring 53 then returns the relay plunger 44 to its upper position, causing the starting switch to be closed again as soon as the vibrator contact 32 comes to rest against contact 31. The starting switch plunger 23 and relay plunger 44 are thus caused to continuously reciprocate at short time intervals determined by the vibrator time delay element 33. This produces a characteristic clicking sound which warns the operator of the inoperative condition and reminds him to open the ignition switch preparatory to taking steps to secure proper starting action.

When the inoperative condition of the engine has been remedied, it is only necessary for the operator to depress the movable switch member 22 until it is retained by the latch 56, whereupon closure of the ignition switch 27 will cause the actuation of the automatic starting mechanism in the usual manner.

In the embodiment of the invention illustrated in Fig. 2, the parts of the automatic starting mechanism are in general the same as illustrated in Fig. 1 and are indicated by similar numerals. In this figure, however, the second or safety switch for the starting circuit comprises a stationary element 80 connected to the starting motor SM and a movable element 81 mounted on the end of the heat-responsive member 68' and electrically connected to the heating element 18' of the starting circuit, the heat-responsive member 68' being so arranged as normally to hold the switch member 81 against the switch member 80.

Means are provided to secure a quick break between the switch members 80 and 81, and to retain the switch member 81 in open position until released by the operator. In the form illustrated, this means comprises a yieldable detent in the form of a plunger 82 carrying a roller 83 of suitable insulating material which is normally pressed against one end of switch member 81 by means such as a spring 84. The switch member 81 is preferably provided with depressions 86 and 87 adapted to conform to the roller 83 and thereby cause a spring 84 to be compressed whenever the switch member 81 moves to or from its closed position.

The operation of this device is substantially similar to that previously described. If the engine fails to start, the heating element 18' causes the heat-responsive member 68' to tend to be deflected in a direction to move the switch member 81 away from the switch member 80. When

this effect becomes large enough to overcome the resistance of the detent 82, the switch member 81 will snap open, thus breaking the starting circuit. When the operator, warned by the ensuing clicking of the starting switch and relay plunger, has taken the necessary steps to secure proper functioning of the engine and starting apparatus, it is merely necessary for him to withdraw the detent 82 by means of the head 83 thereof, thus allowing the heat-responsive member 83' which has now cooled, to move the switch member 81 to closed position. Reclosure of the ignition switch 27 will thereupon cause the automatic starting device to operate in the usual manner.

Although but two embodiments of the invention have been shown and described in detail, it will be understood that various other embodiments are possible and certain changes may be made in the proportions and arrangements of the parts without departing from the spirit of the invention as defined in the claims appended hereto.

What is claimed is:

1. Automatic starting mechanism for internal combustion engines including a starting motor and means for automatically energizing said starting motor if the engine stalls and for de-energizing said motor when the engine starts, and auxiliary means for deenergizing said motor and maintaining the same deenergized in case the motor fails to start the engine in a predetermined time, said energizing and deenergizing means comprising elements rendered effective by the operation of said auxiliary deenergizing means to produce a signal to the operator in case of such failure to start.

2. Automatic starting mechanism for internal combustion engines including a starting motor and means for automatically energizing said starting motor if the engine stalls and for de-energizing said motor when the engine starts, and auxiliary means for deenergizing said motor and maintaining the same deenergized in case the motor fails to start the engine in a

predetermined time, said energizing and deenergizing means comprising elements rendered effective by the operation of said auxiliary deenergizing means to produce a sustained audible signal until stopped by the operator.

3. In automatic starting mechanism for internal combustion engines, a starting circuit including a motor and a starting switch, means including a control circuit for closing said starting switch if the engine stalls, and for opening said switch when the engine starts, and auxiliary means for opening and holding open said starting circuit if the motor fails to start in a predetermined time, said closing and opening means comprising elements controlled by said control circuit and rendered effective by the operation of said auxiliary opening means to produce an audible warning signal.

4. In automatic starting mechanism for internal combustion engines, a starting circuit including a motor and a starting switch having an electro-magnetic actuating plunger, means including a control circuit for closing said starting switch if the engine stalls and opening said switch when the engine starts, and independent means for opening and holding open said starting circuit if the motor fails to start the engine in a predetermined time, said closing and opening means comprising elements controlled by said control circuit and rendered effective by the operation of said auxiliary opening means to cause a continuous periodic reciprocation of the switch plunger.

5. In an automatic starting mechanism for internal combustion engines, a starting circuit including a motor and a starting switch, means for closing the starting switch if the engine stalls, means for opening said switch responsive to a predetermined diminution of the cranking current, a second switch in series with said starting switch for interrupting the cranking current therethrough, and means responsive to a predetermined excess of cranking current for opening said second switch.

FRANK T. CHRISTIAN.
